(57) **CLAIM**

I claim the ornamental design for a cover for electronic device, as shown and described.

DESCRIPTION

FIG. 1 is a front perspective view of a cover for electronic device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1;

FIG. 9 is an enlarged view of the encircled portion in FIG. 3;

FIG. 10 is an enlarged view of the encircled portion in FIG. 4;

FIG. 11 is an enlarged view of the encircled portion in FIG. 7;

FIG. 12 is another left-side view, in which the cover for electronic device is provided in an alternate position;

FIG. 13 is an enlarged view of the encircled portion in FIG. 12; and,

FIG. 14 is another left-side view, in which the cover for electronic device is provided in a second alternate position.

The broken lines in the figures show portions of the cover for electronic device which form no part of the claimed design. The dot-dash lines in the figures represent an unclaimed boundary line and form no part of the claimed design.

The dot-dot-dash broken lines encircling portions of the claimed design that are illustrated in enlargements form no part of the claimed design.
